UNITED STATES PATENT OFFICE.

BERT W. BALL AND MAURIC T. WALTER, OF ST. LOUIS, MISSOURI.

DESIGN FOR A MATCH-SAFE.

SPECIFICATION forming part of Design No. 25,814, dated July 21, 1896.

Application filed February 3, 1896. Serial No. 577,962. Term of patent 3½ years.

To all whom it may concern:

Be it known that we, BERT W. BALL and MAURIC T. WALTER, citizens of the United States, residing at St. Louis, State of Missouri, 5 have invented and produced a new and original Design for Match-Safes, of which the following is a specification, reference being had to the accompanying drawing, forming a part hereof.

10 The figure represents a perspective view of the match-safe.

The leading features of our design may be described as follows:

15 1 represents a suitable rectangular closet or box having an inclined top, and closed on all sides except the front side, which latter is provided with an outwardly-projecting wall.

2. At the base of the box or closet is a receptacle 3, extending above the floor of the

box or closet. The closet has a rear plate or 20 wall 4, serrated along its upper edge, and adjacent to the closet and also carried along the rear plate above the floor of the closet on legs 9 is a V-shaped trough 5, having a rough surface 6. The whole is provided with a base- 2 plate 8.

Having described our invention, what we claim is—

The design for a match-safe, substantially as set forth. 30

In testimony whereof we affix our signatures in presence of two witnesses.

BERT W. BALL.
MAURIC T. WALTER.
